UNITED STATES PATENT OFFICE.

EDGAR M. BIRDSALL, OF BUFFALO, NEW YORK, ASSIGNOR TO MARY BIRDSALL, OF SAME PLACE.

TRACTION-WHEEL.

SPECIFICATION forming part of Letters Patent No. 403,321, dated May 14, 1889.

Application filed December 26, 1888. Serial No. 294,599. (No model.)

To all whom it may concern:

Be it known that I, EDGAR M. BIRDSALL, of Buffalo, in the county of Erie and State of New York, have invented new and useful Improvements in Traction-Wheels, of which the following is a specification.

This invention relates to that class of traction-wheels in which the rim is composed of cast sections secured together and connected with the hub by wrought-iron spokes.

My invention has the object to provide simple means for securing together the several sections of the rim, and also to provide the hub of the wheel with an efficient device for locking the nuts of the spokes in place.

The invention consists of the improvements which will be hereinafter fully set forth, and pointed out in the claims.

In the accompanying drawings, consisting of two sheets, Figure 1 is a side elevation of my improved traction-wheel, partly in section. Fig. 2 is a transverse section thereof. Fig. 3 is a fragmentary cross-section of the rim on an enlarged scale. Fig. 4 is a face view of a portion of the rim. Fig. 5 is a cross-section of the rim at right angles to the axis of the wheel. Fig. 6 is an outside elevation of one of the nut-lock plates. Fig. 7 is a fragmentary cross-section of said plate applied to the hub. Fig. 8 is a fragmentary inside elevation of one of the nut-lock plates.

Like letters of reference refer to like parts in the several figures.

A represents the segmental sections constituting the rim, which are provided in their faces with ribs *a* and openings *a'* in the usual manner for increasing the traction of the wheel. Each rim-section A is provided in opposite sides with a groove or depression, *b*, arranged concentric with the face of the rim, as represented in Fig. 1, so that when the rim-sections are in position a continuous annular depression will be formed on opposite sides of the rim, near the periphery thereof.

C represents annular clamping bands or rings arranged in the annular grooves *b*, and whereby the rim-sections A are firmly secured together. These clamping-bands consist, preferably, of endless hoops or rings, which are placed in the grooves *b* in a heated and expanded condition and contract in the grooves

by cooling, and thereby draw the rim-sections tightly together. The inner portions of the grooves or depressions *b* are preferably undercut, as represented in Fig. 3, so that the 55 clamping-bands will be securely confined in the grooves by the projecting edges of the latter.

D represents the hub of the wheel, and E are the wrought-iron spokes, which are seated 60 with their outer headed ends in openings *e*, formed in the rim. The inner portions of the spokes are secured in perforated radial lugs or enlargements *f*, formed on opposite sides of the hub, by means of screw-nuts *g*, applied 65 to the threaded inner ends of the spokes and bearing against the lugs *f*. The spokes are arranged alternately on opposite sides of the hub in a well-known manner.

H H represent nut-lock plates applied to 70 opposite sides of the hub, and whereby the clamping-nuts *g* are held against turning after being tightened on the spokes. These nut-lock plates consist of disks provided with an annular row of flat-sided recesses or 75 depressions, *i*, which fit over the outer portions of the nuts *g*, as represented in Figs. 2, 7, and 8. The nut-lock plates are secured to the outer sides of the hub by bolts *i'*, as shown in Fig. 2, or by other means. The locking-plates 80 H are provided on their inner sides, at their outer edges, with projections *j*, which close the spaces between the lugs or enlargements *f* and form a smooth joint at these points. These locking-plates also serve as caps, which 85 cover the fastenings at the inner ends of the spokes and give the hub a finished appearance.

I claim as my invention—

1. In a traction-wheel, the combination, with the rim composed of segmental sections and provided in its side with an annular groove or depression, of a clamping-band arranged in said groove, whereby the rim-sections are secured together, substantially as set forth.

2. In a traction-wheel, the combination, with the rim composed of segmental sections, each of which is provided in its side with a concentric groove or depression, and an endless clamping-band secured in said grooves by being shrunk into the same, substantially as set 100 forth.

3. The combination, with the rim and spokes

of a traction-wheel, of a hub, D, provided with perforated radial lugs f, which receive the inner ends of the spokes, screw-nuts g, applied to the inner ends of the spokes and 5 bearing against said lugs, and a locking-plate, H, provided with an annular row of recesses, i, fitting over the outer portions of said nuts, and projections j, formed around the outer edge of said locking-plate and fitting

between the lugs f of the hub, substantially 10 as set forth.

Witness my hand this 21st day of September, 1888.

EDGAR M. BIRDSALL.
